(57) CLAIM

The ornamental design for a set of tower supports, as shown and described.

DESCRIPTION

FIG. 1 is a top plan view of a set of tower supports according to the present invention;

FIG. 2 is a left side view of the present invention;

FIG. 3 is an enlarged bottom plan view of the present invention;

FIG. 4 is an enlarged fragmentary bottom perspective view of the upper right tower support of the present invention shown separately for the clarity of illustration;

FIG. 5 is an enlarged fragmentary bottom perspective view of the upper left tower support of the present invention shown separately for the clarity of illustration;

FIG. 6 is an enlarged sectional view of the present invention, taken along line 6—6 in FIG. 3;

FIG. 7 is an enlarged fragmentary top perspective view of the upper left tower support of the present invention shown separately for the clarity of illustration;

FIG. 8 is an enlarged fragmentary bottom perspective view of the central tower support of the present invention shown separately for the clarity of illustration;

FIG. 9 is an enlarged fragmentary top perspective view of the central tower support of the present invention shown separately for the clarity of illustration;

FIG. 10 is an enlarged sectional view, taken along line 10—10 in FIG. 3;

FIG. 11 is an enlarged sectional view, taken along line 11—11 in FIG. 3; and,

FIG. 12 is an enlarged sectional view, taken along line 12—12 in FIG. 3.

The broken lines represent portions of the design that form no part of the claim.
